UNITED STATES PATENT OFFICE

2,557,376

HEADER FOR CAR DOORS

Frank Ditchfield, Cleveland, Ohio, assignor to
The Youngstown Steel Door Company, Cleve-
land, Ohio, a corporation of Ohio

Application June 15, 1948, Serial No. 33,203

3 Claims. (Cl. 20—26)

1

This invention relates to headers for car doors and more particularly to headers adapted to trap and discharge dust, cinders, rain and the like outwardly of the door openings in the cars.

It is an object of this invention to provide headers for car doors so constructed as to more effectively trap foreign matter which passes over the top of the doors than headers heretofore known and prevent the ingress of such matter into the cars through the door openings formed therein.

A further object is to provide headers for car doors which shall baffle and collect foreign matter passing over the top of the doors that would otherwise gain ingress to the cars through the door openings formed therein and dispose of such matter outwardly of the door openings.

A further object is to provide headers for car doors which shall embody troughs and baffles and be so constructed as to discharge foreign matter from the troughs outwardly of the door openings formed in the cars and prevent foreign matter from being blown into the cars at the points of discharge.

Other objects of the invention will become clear as the description thereof proceeds.

In the drawings forming part of this specification:

Fig. 1 is a fragmentary elevation with parts broken away of the upper portion of a sliding door shown in closed position for a railway car and adjacent portions of the side wall of the car and embodying the instant invention.

Fig. 2 is a vertical section taken on line 2—2 of Fig. 1.

Fig. 3 is a horizontal section taken on line 3—3 of Fig. 1.

Fig. 4 is a horizontal section taken on line 4—4 of Fig. 1.

Referring to the drawings, the numeral 10 designates a portion of a side wall of a railway house car. The construction of the car may be of the well known design designated as an AAR car and embodies a Z-shaped side plate 11 disposed with its web 12 horizontally, one flange 13 depending therefrom and the other flange 14 extending upwardly from the web. As is customary, the side plate extends substantially from end to end of the car and is adapted to support a roof (not shown). The side plate, moreover, defines the top of a door opening 15, the width of which is determined by the front and rear door posts 16 and 17. The front door post is channel-shaped in section and embodies a transversely extending web 18 and forwardly extending inner and outer

2

flanges 19 and 20. The rear door post 17 embodies a transversely extending web 21 and rearwardly extending inner and outer flanges 22 and 23.

5 A door stop 24 is secured to the front door post 16. The door stop embodies a flange 25 riveted to the flange 20 of the door post as by means of rivets 26, an outwardly extending flange 27, a forwardly extending flange 28, an outwardly extending flange 29 and an outwardly and rearwardly extending flange 30. The upper edge of the door stop 24 terminates at the underside of the door header 31 of the instant invention which is hereinafter more fully described in order to permit 15 the header to communicate with a downspout 32. This downspout is formed by the cooperation of the door stop 24, an angular plate member 33 and a Z-shaped door retaining member 34 secured to the downwardly extending flange 13 of the side 20 plate as by means of rivets 35. The construction of the downspout is more fully described and claimed in the patent to F. Ditchfield, 2,362,362, granted November 7, 1944, to which reference is hereby made.

25 An angle member 36 is secured to the outer flange 23 of the rear door post 17 as by means of rivets 37. The outwardly extending leg 38 of the angle member 36 carries a spark and weatherstrip 39 which is adapted to be engaged by a sealing strip 40 secured to the rear margin of an outer sliding door 41 in order to seal the rear portion of the door when it is in closed position.

The door 41 is of well known construction and generally embodies a metallic panel 42 formed with spaced horizontal corrugations 43. The marginal portions of the door are reinforced. As is customary the reinforcement for the front vertical margin of the door is in the form of a substantially channel-shaped member 44 which is adapted to abut the door stop 24 when the door is in closed position. In addition to the sealing strip 40 which also serves as a reinforcement for the rear margin of the door, the latter is reinforced by means of a buffer angle 45. The top margin of the door is reinforced by means of an angle 46 disposed with one leg 47 in vertical position and riveted to the outer face of the door panel as indicated at 48 and the other leg 49 disposed horizontally and extending inwardly toward the side plate 11.

45 The door header 31 embodies an upstanding flange 50 which is secured to the inner face of the side plate flange 13 as by means of rivets 51. The header also embodies an outwardly extending flange 52, an upwardly extending flange 53

which lies in proximate relationship to the inner face of the door and an inwardly and downwardly extending flange 54 which is disposed in proximate relationship to the underside of the inwardly extending flange 49 of the door reinforcing angle 46. The forward edge of the upstanding flange 50 of the door header terminates substantially at the flange 27 of the door stop. Flange 52 of the door header extends outwardly beyond the side plate flange 13 and is coped as indicated at 55 and 56 to substantially conform to the flanges 27 and 28 of the door stop 24 which are overlapped by the header. In this manner direct communication is provided at the front edge of the header between the trough provided thereby and the downspout 32 so that matter trapped within the header may be discharged outwardly of the door opening through the downspout. Flanges 53 and 54 of the header extend continuously into abutment with an inwardly extending flange 51 which is formed on the angular plate member 33. With reference to Fig. 3 of the drawings it will be seen that a portion 58 of the inwardly and downwardly extending flange 54 of the header overlaps a portion of the downspout so that it serves to baffle any foreign matter which may be blown upwardly through the spout and otherwise tend to enter the car without obstructing free communication between the trough and downspout.

At the rear of the door header the upstanding flange 50 terminates at the angle member 36. The outwardly extending flange 52 extends outwardly beyond the side plate flange 13 in overlapping relationship to the flange 38 of angle member 36 and the spark strip 39. Flange 52 is cut away as indicated at 59 so that the remainder of this flange at the rear portion of the header lies upon the spark strip 39. The inwardly and downwardly extending flange 54 of the header is coped, as indicated at 60 and 61, so that the rear portion of this flange extends inwardly beyond the remaining portion of the outwardly extending flange 52 and overlaps the spark strip 39 in such a manner as to baffle any foreign matter which might blow upwardly at the rear edge of the door and tend to find its way into the car. This is more clearly illustrated in Fig. 4 of the drawings. Matter trapped within the trough may be discharged therefrom outwardly of the spark strip 39 and hence beyond the door opening.

It will be apparent from the foregoing description that the header of the instant invention serves to weatherproof the upper edge of the door more effectively than has heretofore been possible. By means of the inwardly and downwardly extending flange of the header any matter which may blow upwardly at the front and rear edges of the door and any matter which may blow over the top edge of the door and be accumulated within the trough of the header will be prevented from finding its way over the header and into the car. In the movement of the car along the track a swirling action is set up within the header trough which heretofore caused such matter as was not discharged from the ends of the header to be blown over the

header and into the car through the door opening. The inwardly and downwardly extending flange, however, forms a complete baffle to the swirling matter and prevents it from entering the car. In the event that any of this matter should lodge upon the flange 54 of the header when the door is open, the slope of the flange will cause such matter to gravitate into the trough of the header rather than into the car. It will be apparent that numerous changes and modifications in the details of the invention will be clear to those skilled in the art. It is intended, therefor, that all such modifications and changes be comprehended within this invention, which is to be limited only by the scope of the claims appended hereto.

I claim:

1. In a railway car having a side wall provided with a door opening and a sliding door for closing said door opening secured to said side plate, an outwardly extending flange, a flange extending upwardly from said latter flange in spaced relationship to said side plate and a baffle flange extending inwardly from said upwardly extending flange and terminating in spaced relationship to said side plate, said inwardly extending baffle flange being spaced from said door.

2. In a railway car having a side wall provided with a door opening, a side plate at the top of said door opening, a door for closing said door opening, an inwardly extending reinforcing flange at the top of said door, a header secured to said side plate, an outwardly extending flange terminating in proximate relationship to the inner face of said door, a flange extending upwardly from the outer edge of said latter flange and a baffle flange extending inwardly from said upwardly extending flange and terminating in spaced relationship to said side plate, said inwardly extending baffle flange lying in proximate spaced relationship to said inwardly extending door reinforcing flange.

3. In a railway car having a side wall provided with a door opening, a side plate at the top of said door opening, a door for closing said door opening, an inwardly extending reinforcing flange at the top of said door, a header secured to said side plate, an outwardly extending flange terminating in proximate relationship to the inner face of said door, a flange extending upwardly from the outer edge of said latter flange and a baffle flange extending inwardly from said upwardly extending flange and terminating in spaced relationship to said side plate, said inwardly extending baffle flange sloping downwardly and lying in proximate spaced relationship to said inwardly extending door reinforcing flange.

Certificate of Correction

Patent No. 2,557,376

June 19, 1951

FRANK DITCHFIELD

It is hereby certified that error appears in the printed specification of the above numbered patent requiring correction as follows:

Column 4, line 20, after the word "opening" insert, *a side plate at the top of said door opening, a header;*

and that the said Letters Patent should be read as corrected above, so that the same may conform to the record of the case in the Patent Office.

Signed and sealed this 4th day of September, A. D. 1951.
